IGNITION DEVICE FOR USE WITH SAFETY
FUSES OR THE LIKE

David E. Pearsall, Pittsburgh, Pa., and John D. Rich, West Hartford, Conn., assignors to The Ensign-Bickford Company, Simsbury, Conn., a corporation of Connecticut

Application March 16, 1939, Serial No. 262,144

5 Claims. (Cl. 102—8)

Our present invention relates to a cord-like ignition device for use in initiating a number of explosive charges, as in mining, military uses and in pyrotechnic displays, and aims to provide certain improvements therein.

The primary object of our invention is to provide such a device as will insure in mine blasting a safe and simple method of igniting a number of safety fuses used in a blasting round by the single application of a flame, glow or other source of heat to a given point which may be located at any desired distance from the actual mine fuses and thereby afford the shot-firer improved conditions of safety. Among the further objects of the invention the following may be enumerated: To provide an ignition device whereby a number of holes of a blasting round may be fired in any desired rotation without trimming the fuse ends, or whereby any number of holes can be caused to fire simultaneously while the remaining holes may be fired in any desired order.

Prior to our invention it has never been found practicable to ignite rounds of safety fuse from a distance by means of an ignition device because of the inability to control the intensity of the flame and the burning speed of such device. Neither has it been possible to make such device sufficiently flexible, settable and moisture-proof to permit its use in damp places. Moreover, all prior devices with which we are familiar were consumed in burning so that they would not remain supported in their original position, and in consequence would fall and discharge incandescent sparks or flame onto other parts of the ignition device, or onto the safety fuses so as to destroy the rotational order of the round and create other serious hazards.

The foregoing various objections and difficulties are overcome by our invention, which, in its underlying concept, consists of a cord-like member which can be produced in continuous lengths, having a non-inflammable central settable supporting element and a covering for said central element that will provide a firm base for carrying a combustible medium. The combustible medium is preferably of a character which will burn at a substantially uniform rate and project a regulated flame from its surface but will not disturb the position or arrangement of the supporting element which will remain firmly in place after the fire has passed, although it may be partly demolished by the force of the subsequent explosion.

The invention will be better understood from

the detailed description which follows when considered in connection with the accompanying drawing wherein the single figure shows a fractional side elevation of an ignition device or cord embodying our invention, with parts thereof being broken away to better illustrate the constructional details thereof.

Referring to the drawing, the ignition device which is of cord-like appearance may be said to consist of a central flexible and settable wire or the like 10 having upon its surface an adhesive coating 11 over which is countered or disposed in encompassing relation a plurality of strands of textile or like yarns 12. The central structure formed by the wire 10 and textile strands 12 provides a support or absorbent base for a powder train or coating 13. Over the powder train are disposed textiles 14 wound in contra-direction giving the appearance of a basket weave and providing substantially uniformly spaced exposed areas 15 of the powder train. The whole structure is then given a waterproof coating 16 of lacquer, wax or other suitable material.

Since the function of the ignition device is to continuously ignite safety fuses and similar burning media to which it may be connected at any point along its length, it is important that the projected flame be continuous and of sufficient intensity to satisfactorily ignite the fuses or the like.

A preferred form of ignition device which we have found to give satisfactory results consists of a #25 gauge annealed, tinned steel wire countered with six strands of 15/4 ply cotton yarns. A thin coating of special adhesive is applied to the wire causing the yarns to cling thereto. After drying, this core structure is then coated with a powder paste consisting of mealed black powder in a binder solution of nitrocellulose. By varying the amount of the ingredients in the powder base the rate of burn may be controlled between limits of approximately one foot in a second to one foot in twenty seconds. The protective covering of textiles consists of four pairs of 16/1 ply yarn applied in a counter-clockwise direction and four pairs of similar yarn applied in a clockwise direction. The waterproofing composition which is used for coating the assembly may be any desired wax composition.

An ignition device as described, when ignited will project a regulated, continuous, intense flame from its surface while burning, thus rendering the ignition device particularly adapted and suitable for continuous or sequential igniting of safe-

ty fuses or similar burning media to which it may be connected at any point along its length.

Although we have shown and described a preferred embodiment of our invention, it will be appreciated that the supporting structure, as well as the powder train media may be different from that hereinbefore specifically described. For example, in lieu of the central supporting wire, it is possible to use an asbestos cord or other non-combustible, settable material. Where an asbestos core is substituted for the wire it may also serve to replace the yarn counteracting 12 and the sizing 11 and provide a central supporting structure for the powder train. Also, in lieu of the black powder base specifically mentioned, the powder train may be made from powders of the thermite (non-gaseous) type. It will also be appreciated that the burning speed of the ignition device might be varied by twisting together two or more slower burning powder-coated media as well as by varying the powder paste composition and the character of the waterproofing composition with which the ignition device is coated.

It will thus be seen that while we have shown and described a preferred embodiment of our invention, the concept underlying the same is of such character and scope as to permit of variations in the specific construction disclosed, within the range of mechanical and engineering skill, without departing from the spirit of the invention.

What we claim is:

1. An ignition device comprising a flexible element capable of being formed in any desired shape independently of any supports and remain so during and after burning, a core of rapidly combustible material supported by said flexible element and a covering for said core, said covering providing substantially uniformly spaced exposed areas of the core of rapidly combustible material, whereby said ignition device as it burns will project a regulated flame from its surface.

2. An ignition device comprising a flexible element capable of being formed in any desired

shape independently of any supports and remain so during and after burning, counteracting yarns encompassing said flexible element, a rapidly combustible material supported by said counteracting yarns, a partial covering for the combustible material so applied as to leave substantially uniformly spaced exposed areas of the rapidly combustible material and a waterproof coating encompassing the assembly.

3. An ignition device comprising a central wire capable of being formed in any desired shape and so remain independently of the means by which it is supported, a coating of rapidly combustible material supported by said wire, and a covering for said structure, said covering providing substantially uniformly spaced exposed areas of the rapidly combustible material whereby the ignition device as it burns will project a regulated flame from its surface.

4. An ignition device comprising a central wire capable of being formed in any desired shape and so remain independently of the means by which it is supported, counteracting yarns encompassing said central wire, a coating of rapidly combustible material supported by said counteracting wire, and a covering for said structure, said covering providing substantially uniformly spaced exposed areas of the rapidly combustible material, whereby the ignition device as it burns will project a regulated flame from its surface.

5. An ignition device comprising a flexible wire capable of being formed in any desired shape and so remain independently of the means by which it is supported, counteracting yarns encompassing said wire, a coating of rapidly combustible material consisting of mealed black powder with a binder agent supported by said counteracting wire, a textile covering for the powder coating so applied thereover as to leave exposed areas of the powder for controlling the size of the surface flame provided by the powder while burning, and a waterproof coating encompassing the assembly.
